UNITED STATES PATENT OFFICE.

ALBERT A. HEYMAN, OF BALTIMORE, MARYLAND, ASSIGNOR OF ONE-HALF TO
TAZEWELL T. THOMAS, OF BALTIMORE, MARYLAND.

APPARATUS FOR REPRODUCING BASE-BALL GAMES.

1,126,636.

Specification of Letters Patent.

Patented Jan. 26, 1915.

Application filed June 7, 1913. Serial No. 772,284.

To all whom it may concern:

Be it known that I, ALBERT A. HEYMAN, a citizen of the United States of America, residing at the city of Baltimore, State of Maryland, have invented certain new and useful Improvements in Apparatus for Reproducing Base-Ball Games, of which the following is a specification.

This invention relates to an apparatus for 10 reproducing base ball games or other incidents, acts or series of incidents at any distance from the point where they occur and almost simultaneously with their occurrence.

The result is accomplished by means of 15 moving picture apparatus modified to suit the conditions presented and the invention resides in the method and in the apparatus as thus modified.

Though other incidents may be as conveniently handled, the reproduction and 20 presentation of base ball games will be used as an example for the purpose of illustrating the invention.

The operation consists in first analyzing 25 the game to determine the number and nature of the possible plays or those which are not of extremely infrequent occurrence, and it should be noted that the nature of the game is such that practically all the plays 30 can be thus determined and standardized. After this has been done, comparatively short film sections are prepared, each illustrating the condition of the diamond with the players thereon and their actions during a particular play. The film sections 35 thus prepared are preferably provided with means at their ends whereby they may be joined to form a continuous film though they may be merely lapped and cemented.

40 The game is reported by telegraph or telephone as it occurs, the report being received by an attendant at the place of exhibition. The film sections illustrating the standardized plays are assorted and indexed, and as the report comes in, the appropriate 45 sections are selected, attached end to end, and a continuous film illustrating each inning as reported is thus prepared, the game being presented to the audience inning by inning, one inning being received and set 50 up while the previous one is being reproduced.

The invention, in so far as it resides in the apparatus, relates to the film sections 55 illustrating the individual plays adapted to

be joined together to form continuous films. These are arranged, when ready for use, in sets, each set illustrating corresponding plays or portions of the game, the showing of the sections of each set being varied in detail so as to show a large number of equivalent or corresponding plays. The whole outfit consists of a series of these sets, so that by choosing a film section from each of several sets and joining them in sequence, a continuous film is formed, showing the plays as they have occurred or as the operator may determine. These may be provided at their ends with tabs preferably half the thickness of the film which is usually of celluloid, the ends of the celluloid strips being cut away or reduced to half their normal thickness so that the end of the tab may be placed in the reduced portion or notch thus formed, the reduced film and the superimposed tab being of a thickness equal to that of the remainder of the film. Thus when the free portions of the tabs at the meeting ends of two films are superimposed on each other, the outer end of each tab abuts against the adjacent end of the other film, forming a continuous strip of uniform thickness, and for the purpose of joining the sections to form the strip, the contacting surfaces of the tabs are pasted or cemented together preferably with an adhesive which can be conveniently softened and removed for the purpose of disjointing the films, or the tabs may be omitted and the films lapped and cemented.

In the accompanying drawing I have illustrated a portion of the apparatus to which my invention relates in its preferred form, and I have also shown a battery of moving picture machines arranged to project the views of the game upon the screen.

Figure 1 is an enlarged perspective of the meeting ends of two film sections, one end tab being partially unattached and rolled up for purposes of illustration. Fig. 2 is a longitudinal section of the same. Fig. 3 is a reduced plan, portions of the films being broken away to make it possible to illustrate several sections. Fig. 4 is a diagram showing a battery of three moving picture machines as they are best used in reproducing ball games and the like according to my method.

The apparatus as shown consists of film sections 1 reduced at 2 to half their normal 1

thickness, forming shoulders 3 spaced back from the ends a distance sufficient to provide for affixing of the tabs 4. These consist of paper cloth or other tough and flexible material and are of sufficient length so that when seated in the rabbet formed in the film by reducing its thickness at 2 and having their ends abutted against the shoulder 3, there is a free portion beyond the film forming a tab of sufficient length so that it can be joined to a similar tab on another film by means of glue or paste or some mechanical device. The connected films thus joined will resist all ordinary tensions which occur in the exhibiting machine, forming a continuous built-up or assembled film which may be used as long as it is of interest. The joint thus formed is shown in Fig. 2. As there shown the end of each tab at 5 abuts against the extreme end 6 of the reduced portion 2 of the adjacent film, the film proper and the joint being continuous, smooth and of uniform thickness.

The film 1 is preferably of the perforated type which is capable of being positively driven, though any other variety of film may be utilized within the scope of the invention. The perforations are indicated in the drawing by reference character 7.

In Fig. 3 a plan of the assembled film 8 is shown. In this figure the beginning and end of the adjacent film sections is indicated, and as hereinafter pointed out, it is important that the views adjacent these joining ends on the two adjacent films be either identical or substantially identical so as to present continuous action.

Various games are analyzed and the plays standardized, and the film sections showing the diamond during these plays are prepared after the usual manner, a troop of players making a specialty of this work being retained for this purpose. In this connection it will be apparent that while certain identical plays are frequently repeated in the course of each game, the preceding and following plays often differ in a way which would require a different setting at the beginning and ending of certain plays which are otherwise identical. Therefore, certain of the plays must be illustrated by several different films varying as to the opening or closing views according to the plays which precede and follow the particular one in question; and as far as possible the diamond is brought to a uniform condition at the end of each play so that the film sections may be as nearly as possible identical at their opening and closing scenes and thus capable of being joined in the greatest number of permutations and combinations to show continuous action. The word "condition" as used herein relates to the position and identity of the players present on the diamond, uniform condition

being when the same players are present in substantially the same positions.

For reproducing base ball games the film sections may be divided into a chosen number of main groups, each group illustrating correlated plays. Group No. 1 may include all plays made by batter, pitcher, catcher, etc., with the bases clear. Group No. 2 may include all plays made on the field and diamond with a man on first base. Group No. 3 includes all plays made with a man on second base. Group No. 4 includes all plays made with a man on third base. Group No. 5 includes all plays made with men on first and second bases. Group No. 6 includes all plays made with men on first and third bases. Group No. 7 includes all plays made with men on second and third bases. Group No. 8 includes all plays made with men on first, second and third bases. However, the plays may be otherwise grouped and subdivided within the scope of the invention.

All plays in group No. 1 commence with a man at the bat and no runners are shown on any of the bases. The ending scene, however, may show a man safe on anyone of the bases or may show the batter coming home, or the closing scene may show a man out at the bat, or on first, second, third or home. Thus all plays in group No. 1 ending with the batter out at the bat or while running around bases, may be succeeded by some other play taken from group No. 1 but cannot be followed by a play from any other group, and all other plays of group No. 1 that end with the batter safe on first base, may be followed by some play taken from group No. 2 and from no other group. This rule is true of all the various plays in the different groups. Those plays ending with all men on bases out and batter out can be followed only by plays in group No. 1, and all plays in the different groups ending with a man safe on first base can be followed by plays in group No. 2. All plays ending with a man safe on second may be followed by plays from group No. 3. All plays ending with a man safe on first and third can be followed by plays taken from group No. 5 and from no other group.

As I have stated, the game is reported by telephone or telegraph to the place of exhibition at which a moving picture machine or preferably a battery of machines is provided. The film sections are indexed and arranged so that they are easily identified and accessible, and a group of several attendants is provided to manipulate them. Each inning is set up as reported and exhibited while the following inning is being completed, and a continuous film is formed for each series of plays preferably covering the entire inning. As the plays are reported, the corresponding film sections are se-

5 lected and affixed to each other so as to illustrate the plays in the order in which they are made, the first view of each section in the built-up film being identical with the last view in the preceding section so that the film when exhibited will present substantially continuous action.

10 The films are inserted in turn in the moving picture machines, three of which, 9, 10 and 11, as shown, may be used. These are focused on the screen 12, and in order that there may be no delay on account of the necessity for holding one machine inoperative while the film is inserted, the films 15 are inserted alternately in the machines of the series, the exhibition being substantially continuous.

15 I have thus described and shown an apparatus embodying my invention. However, this is for the purposes of illustration and the specific terms herein are used in their description rather than in their limiting sense, the scope of the invention being defined in the claims.

20 25 I claim—

1. Apparatus for reproducing and exhibiting base ball games, the same consisting of a series of sets of sections of moving picture film, the sections of each set each 30 showing a selected portion of an act or game, the sections of each set showing corresponding and interchangeable acts or portions of the game, the showing of these corresponding sections being varied, the subjects of the sections of the different sets being 35 acts or portions of the game which in the natural order of things may follow each other, so that a number of sections taken from each of several sets joined in sequence, will illustrate any one of several continuous 40 innings or games capable of being illustrated by different combinations of the sections taken one from each of several sets.

2. Apparatus for reproducing and exhibiting base ball games, the same consisting of a plurality of sections of moving picture film, each showing a selected portion of an act or game, there being a number of sections showing corresponding acts or portions 50 of different games with varying detail, the portions of the game illustrated by the different sections being such that a series of sections showing different portions joined in sequence, will illustrate a continuous 55 act or game, the first view of each section being the same as substantially the last of the preceding section whereby it is possible to vary the selection of corresponding sections and thus change the course of the 60 game or series of acts reproduced.

3. Apparatus for reproducing and exhibiting base ball games and other acts or series of acts consisting in a plurality of sections of moving picture film, the sections being 65 arranged in sets, the films of each set

showing corresponding portions of different games or corresponding acts of different series, the same being slightly varied according to the relation of such different games and acts to each other, each complete apparatus including a number of such sets, the subjects of the different sets being acts or portions of games occurring in sequence so that the sections can be joined in series, sections from several sets forming a single film 70 showing a continuous series of acts or a game, and means for temporarily joining the film sections whereby by varying the selection of film sections from any of the different sets, the course of the game reproduced may be changed as desired.

4. Apparatus for reproducing and exhibiting base ball games consisting in a plurality of sections of moving picture film, the sections being arranged in sets, the films 85 of each set showing corresponding portions of different games or corresponding acts of different series, the same being slightly varied according to the relation of such different games and acts to each other, each complete apparatus including a number of such sets, the subjects of the sets being acts or portions of games occurring in sequence so that the sections can be joined in series, sections from the different sets forming a single film 90 showing a continuous series of acts or a game, the first and last view of each film section being such that the films can be joined to give an effect of continuity, and means for joining the film sections. 100

5. Apparatus for reproducing and exhibiting base ball games and other acts or series of acts, the same consisting of a series of sets or sections of moving picture film, the sections of each set each showing a selected portion of an act or game, the sections of each set showing corresponding and interchangeable acts or portions of the game, the showing of these corresponding sections being varied, the subjects of the sections of the different sets being acts or portions of the game which in the natural order of things may follow each other, so that a number of sections taken from each of several sets joined in sequence, will illustrate 110 any one of several continuous acts or games capable of being illustrated by different combinations of the sections taken from each of several sets. 115

6. Apparatus for reproducing base ball 120 games by means of moving pictures which includes a number of sections of moving picture film, each of which carries pictures of a particular play which might occur in the course of a game of base ball; a different section for each different play to be represented and for each different condition of the field during each given play, the whole being so adapted and related substantially as hereinbefore described, that one combina- 125

tion of sections may be assembled to represent the continuous action of an inning or game of base ball, and another combination of sections may be assembled to represent the continuous action of a different inning or game of base ball.

7. Apparatus for reproducing base ball games by means of moving pictures, which includes a multiplicity of sections of moving picture film, each of which sections carries pictures of a particular play which might occur in the course of a game of base ball, the sections being related in groups, the closing pictures of all the sections of one group showing substantially the same general condition of the field as the opening

pictures of the group which may be shown thereafter, the whole being so adapted and related as hereinbefore described, that one combination of sections may be assembled to represent the continuous action of an inning or game of base ball, and another combination of sections may be assembled to represent the continuous action of a different inning or game of base ball. 20

Signed by me at Baltimore, Md. this 5th day of June 1913. 25
